USE OF SOLVENT LIQUIDS IN CRACKING
HEAVY RESIDUAL OILSGale L. Adams, Los Angeles, Calif., assignor to
Socony-Vacuum Oil Company, Incorporated,
New York, N. Y., a corporation of New YorkNo Drawing. Application May 21, 1938,
Serial No. 209,378

4 Claims. (Cl. 196—50)

The invention pertains to the art of cracking the heavy, residual petroleum oils known generically as black oils and containing relatively large proportions of asphaltic substances and paraffin wax.

The primary object of the invention is to permit the cracking of residual oils which are of too great viscosity and too high a carbon content to permit them to be cracked in the conventional manner.

A corollary object of the invention is to afford the maximum yield of uncracked (so-called "virgin") gas oil by simple distillation of the black oil followed by the cutting back of the viscous reduced product with a highly refractory cracked product having superior viscosity cutting properties for the stock charged to the cracking furnace.

It is conventional practice to crack black oils, either for the production of motor fuels and other volatile products or for the reduction of viscosity and pour test. It is also well known to separate from the products of the cracking operation a fraction boiling above the boiling range of gasoline and to return this fraction as recycle stock to the black oil feed, to be cracked with it.

In conventional operations such as this it is impossible to fit the cracking temperature to the wide range of hydrocarbons present. If a sufficiently high temperature be used to appreciably crack the cycle stock, the run is of short duration due to overcracking of the contained pitch. On the other hand, if the temperature be lowered to the optimum point for the asphaltic constituents, the cycle stock is not materially altered. The process to be described makes possible maximum yields from all products charged to the cracking furnace by providing selective cracking conditions for the highly reduced asphaltic residues.

Heretofore it has been impossible to crack black oils having a viscosity much in excess of 300 seconds Saybolt furol at 122° F. without excessive carbon formation and the rapid choking of tubes. I have discovered that it is possible to crack, without undue carbon deposition, a straight run residual oil of much higher viscosity, up to as much as 4,000 seconds S. F. at 122° Fahr., by diluting the black oil feed with a relatively small proportion of a heavily cracked and refractory fraction of relatively low boiling point and of low viscosity. The addition of this solvent oil, when properly selected, enables me to disregard the cracking

temperature of the small quantity of recycled oil and to crack at the temperature most favorable to obtaining whatever results may be desired from the cracking of the black oil.

The first requirement in the oil selected as a solvent oil is that it shall have a low viscosity and a well developed power of dissolving the bituminous constituents of the black oil, these characteristics permitting a relatively small proportion of the solvent oil to effect a relatively large reduction in viscosity. The second is that it shall be so refractory as to be substantially unchanged at the temperature at which the black oil is to be cracked. The third is a boiling range which permits it to be vaporized at the preferred cracking temperature, thus aiding in purging the furnace tubes of carbon as formed, the vapors subsequently being fractionated out of the cracked products for return to the feed. A solvent oil consisting predominantly of aromatic hydrocarbons within the required boiling range is particularly desirable for this use.

While a cracked distillate meeting these requirements may be obtained from various cracking operations, a typical and particularly suitable solvent oil is the fraction from a heavy gasoline or kerosene reforming operation which boils above the boiling range of gasoline. Such a solvent was used in the tests described immediately below, this oil having the following properties:

Gravity, A. P. I.	degrees	19.0
Boiling range, I. B. P., 454° F., dry point	degrees	598
Minimum appreciable cracking temperature		
under conditions of test	degrees	930 to 940
Viscosity, Saybolt Universal at 100° F.	seconds	35.6

An oil having this relation of gravity to viscosity and boiling range is very deeply altered from its original constitution as a petroleum fraction and consists to an important extent of ring hydrocarbons. We recognize that a satisfactory oil of this character can often be built up from the reaction products in a normal viscosity breaking cycle, and that it is not necessarily essential that an extraneous solvent oil be used.

In order to illustrate the working out of this process and its utility under certain commercial conditions, the following experimental runs were made. These are all based on an initial quantity of 10,000 barrels of a 125 viscosity asphaltic and waxy residuum from light California crude (vis-

cosities are in seconds, Saybolt furol at 122° F. unless otherwise stated).

In the operation recorded in column 1 the 125 viscosity residuum was passed through the cracking operation as is (without any further reduction) and in a once-through treatment (without recycle).

In the operation shown in column 2 this 125 viscosity residuum was reduced by further distillation to 1800 seconds viscosity and this reduced stock was fed to a once-through cracking operation without any addition of solvent oil.

In the operation recorded in column 3 the 125 viscosity residuum was reduced by distillation to 312 seconds viscosity and this stock was fed to the cracking operation without the addition of solvent oil but with recycle of the gas oil produced in the operation. The volume of the recycle was to the volume of the fresh feed as 0.9 is to 1.0.

In the operation shown in column 4 the 125 viscosity residuum was reduced by distillation to 1800 seconds viscosity and cut back to 340 seconds viscosity by admixture with 13.0% of its own volume of the reformer solvent oil described above. The cut-back stock was then passed through a once-through cracking operation. As this operation proceeded the unaltered solvent oil was fractionated out of the products of the operation and returned to the feed, this returned uncracked solvent oil constituting a recycle having the ratio to the fresh feed of 0.13:1.00.

The operation recorded in column 5 was the same as operation 4 except that the original stock was reduced to a viscosity of 3400 seconds and cut back to 340 viscosity by the addition of 15.7% of its volume of solvent oil, the recycle ratio being thus 0.157:1.000.

In the five cracking operations the conditions were intentionally adjusted to give, as nearly as possible, the same yield of gasoline figured back to the original 10,000 barrels of 125 second residuum. In all of these operations a portion of the gas oil yielded by the cracking operation was used to cut back the cracked residuum to fuel oil viscosity and the net yield of gas oil stated is that remaining after this portion was so utilized.

All yields in the following table are based upon a total volumetric yield of 100 per cent of liquid products on the 125 second straight run residuum charge. In addition a gas yield of from 2 to 4 per cent by weight of charge is produced. This is due to the change in specific gravity relationship from charge to products.

The principal utility of this process is found in two of its aspects: the obtaining of large yields of straight-run gas oil, and a major increase in the capacity for producing low viscosity and low pour point fuel oil of any given piece of cracking equipment.

Regarding the first named, gas oils are in large and increasing demand as Diesel engine fuel, and for this purpose the straight run gas oils are more desirable than those produced by cracking. Further, if the purpose of the operation be to produce the maximum quantity of gasoline rather than gas and fuel oils, the cleanest operation and the maximum economy are obtained by cracking the gas oils in a separate operation rather than in a recycling operation in which the asphaltic constituents of the crude are present.

The second named feature is, however, the major element of utility, the process lending itself particularly to viscosity breaking operations in which fuel oil rather than gasoline is the product particularly desired. For this purpose, a very great increase in the output capacity of any given cracking installation is produced by the method above described, as is shown by the following figures indicating the yields of products from a

15 Operation No. 1 gives a high yield of fuel oil, which is defective as regards pour point. Operation No. 5 is also deficient in this regard and it is possible that the optimum point of reduction has been passed in this run.

20 Operation No. 2 gives the highest yield of all products but this operation, without the addition of the solvent, is merely the statement of a desideratum as the operation is commercially impracticable. The high figure for sediment 20 shown in the figures for properties of products indicates the liability to coking, and in fact this run was not completed because of the rapid choking of the coil by carbon. It is the addition of the solvent oil which makes this operation 25 practicable and substantially free from the carbon accumulation which has heretofore prevented the cracking of these heavy black oil residues.

30 It will be noted that the addition of the solvent oil in runs 4 and 5 reduces only slightly the output capacity of the apparatus and that it increases by approximately four the octane number of the gasoline produced over that yielded by runs in which the solvent was not present. 35 The reason for this result is not known to me, but it was observed equally in other experiments in which cracking temperatures were raised and lowered to produce more and less gasoline and 40 appears to be the direct result of the addition of the solvent oil.

45 It may be pointed out that the once-through operation of run 1 is not commercially desirable because of the low yields of products and the high pour point of the fuel. Run 3, however,

is the normal type of commercial recycle operation. As a consequence, the real comparison of cracking unit capacity is between the 5,937 barrels of run 3 and the 12,840 and 13,969 barrels of runs 4 and 5 respectively.

5 It is recognized that the enhanced output of the cracking unit in runs 4 and 5 over that obtained in run 3 is dependent on the provision of additional distillation capacity sufficient to care for the additional reduction required to bring the 10 cracking still charging stocks down to a reduced bulk. It is well known, however, that distillation equipment and distillation operation are much less costly than the equipment and operation required in cracking, and that the cost of 15 distillation thus by no means offsets the economy incident to increased production from the cracking unit.

I claim as my invention:

1. In the cracking of heavy petroleum residuum containing asphaltic substances, the steps of: reducing said residuum by a non-cracking distillation to a viscosity exceeding that at which said residuum may be cracked without excessive carbon formation, said viscosity being substantially greater than 300 seconds Saybolt furol at 122° Fahr.; blending with said reduced residuum a solvent oil, characterized by low viscosity and high solvent power for asphaltic substances, in amount required to produce a blend having a 30 viscosity of about 300 seconds Saybolt furol at 122° Fahr.; and subjecting said blend to a temperature at which the constituents of said residuum are cracked and at which said solvent oil is substantially uncracked.

35 2. A process substantially as and for the purpose set forth in claim 1, in which said residuum is reduced to a viscosity not less than 1800 seconds Saybolt furol at 122° Fahr. prior to being blended with said solvent oil.

40 3. A process substantially as and for the purpose set forth in claim 1, in which said solvent oil consists predominantly of aromatic hydrocarbons.

45 4. A process substantially as and for the purpose set forth in claim 1, in which said solvent oil is a highly cracked and refractory petroleum product.

GALE L. ADAMS. 50
